UNITED STATES PATENT OFFICE

JAMES T. ELLIS, OF SULPHUR MINE, LOUISIANA

PIPE CUTTER

Application filed October 9, 1931. Serial No. 567,735.

This invention relates to pipe cutters.

It has for its general object the provision of a new and improved cutter particularly adapted to be lowered into a casing stuck in a well, and to cut the casing into any desired number of sections in order that it may be removed.

A specific object of the invention is to provide a cutter through which water or other cleaning and cooling fluid may be forced at all times when it is in the casing; embodying a movable cutting blade, and means to feed the blade by gravity, said means being normally held in its inactive position and released by the water; and means to automatically notify the operator when the casing has been cut; the construction and combination of the elements being such that the casing is efficiently cut in two so that the lower section of the casing has a flared upper end through which the cutter may be inserted easily to again cut the casing at a lower point.

Other objects will hereinafter appear.

The preferred embodiment of the invention is illustrated by the accompanying drawing, of which Fig. 1 is a sectional elevation of the pipe cutter in a casing, the parts being shown in their inactive positions; Fig. 2, a horizontal section on the line 2—2 of Fig. 1; Fig. 3, a view similar to Fig. 1, the parts being shown in their active positions; and Fig. 4, a detailed view of the blade holder.

In the drawing, the casing or other pipe to be cut in sections is indicated at 1. The pipe cutter body 2 may comprise an upper section 3 and a lower section 4. The upper section 3 may be connected by suitable threads 5 to a string of tubing, not shown, by which the cutter is lowered into and rotated in the casing, and through which water may be pumped to the cutter. The upper and lower sections 3 and 4 are connected by threads 6, and the lower section 4 may be tapered as indicated at 7 for insertion in the casing.

Between the upper and lower sections 3 and 4 of the cutter body is a partition 8, whereby the interior of the cutter body is

divided into an upper chamber 9 and a lower chamber 10.

Reciprocable in the upper chamber 9 is an actuator support 11 comprising a ring in which is slidably an actuator 12. The actuator 12 comprises a rod extending downwardly through the partition 8 and into the lower chamber 10. The actuator 12 has an upper solid section 12a, an intermediate perforated hollow section 12b, and a lower hollow section 12c. The sections 12b and 12c are connected by a collar 13 which normally rests upon the actuator support 11 and serves to limit the upward movement of the support 11 on the actuator 12. The actuator 12 is thereby normally held in its inactive position shown by Fig. 1. In the upper chamber 9 and about the actuator 12 is a spring 14 bearing at its lower end on the partition 8 and at its upper end against the actuator support 11, and serving to yieldably hold the support 11 in its active position.

In communication with the lower chamber 10, the body has a radial slot 15 in which a blade holder 16 is pivoted at 17. Carried by the holder 16 above its pivot 17 is a cutting blade 18 having a cutting edge 19 extending upwardly and outwardly from the longitudinal axis of the body. Carried by the holder 16 between the blade 18 and the pivot 17 is a dog 20 having pipe-engaging teeth 21.

The actuator 12 has a wedge or inclined portion 21 to engage the holder 16 and swing it on its pivot 17 from the inactive position shown by Fig. 1 to the active position shown by Fig. 3. When the wedge 21 is moved by the spring 14 from the position shown by Fig. 3 to the position shown by Fig. 1, the spring 17 swings the holder 16 back on its pivot 17 from the position shown by Fig. 3 to the position shown by Fig. 1.

The numerals 23 and 24 indicate spacers that project radially from the body 2. The blade 18 and spacers 23 and 24 are at substantially equal distances apart on the periphery of the body 2, and the spacers serve to prevent objectionable lateral movement

of the cutter in the casing when it is in operation.

The pipe cutter may be used as follows:

After the cutter body 2 has been lowered 5 to the desired position in the casing 1 by the string of tubing, not shown, water may be pumped through the string of tubing and upon the actuator support 11. A portion of this water will pass at all times through 10 the perforations in section 12b of the actuator, and then downwardly through the sections 12b and 12c and out of the lower end of the body to remove the cuttings and keep the blade 18 cool. When the pressure of 15 the water is sufficient, the actuator support 11 will be moved downwardly against the resistance of the spring 14 and away from the collar 13. The actuator 12 is then free to be moved by gravity into its active position, and, when it does, the wedge 21 will 20 engage the holder 16, swinging it outwardly on its pivot 17 to move the blade 18 into its active position. The cutter body 2 will then be rotated by the string of tubing, not 25 shown, and the casing 1 will be cut. When the casing 1 has been cut, as shown by Fig. 3, the dog 20 will engage the casing to resist further rotation of the cutter in the casing. The operator will be thereby notified that 30 the casing has been cut. The pressure of the water may then be decreased to permit the spring 14 to move the actuator support 11 upwardly, whereupon the support 11 will engage the collar 13 to return the actuator 35 12 to its inactive position; and as the wedge 21 will be moved away from the holder 16, the spring 22 will return the holder 16 to its inactive position. The movement of the 40 parts is from the position shown by Fig 3 to the position shown by Fig. 1. The cutter may then be lowered to any desired point in the casing and again operated to cut the casing at that point. Or the cutter may be 45 removed from the casing, and the upper section of the casing may be removed from the well by any suitable fishing tool, not shown, after which the cutter may be lowered into the lower section of the casing to cut the casing again.

It will be obvious from the foregoing that 50 cleaning and cooling fluid may be forced through the cutter at all times; that the cutting blade is positively urged by the actuator into cutting engagement with the casing; that the operator will be promptly notified when the pipe has been cut, and that the apparatus cannot give a false notice to that effect; that the cutting blade cuts the casing 55 so that the upper end of the lower section 1a is flared, as indicated at 1b and the cutter may easily be lowered further into the casing, the cutting blade 18 being forced by the lower section 1a of the casing back into its inactive position if the spring 22 fails to 60 function.

Various objects and uses of this invention, other than the above, will be apparent to those skilled in the art.

I claim:

1. A pipe cutter having a hollow body; a cutting blade movably mounted in said body; a blade actuator in said body and movable into its active position by gravity; an actuator support normally holding said actuator in its inactive position and arranged to be moved by fluid forced into said body to release said actuator. 70

2. A pipe cutter having a hollow body; a cutting blade movably mounted in said body; a blade actuator in said body and movable into its active position by gravity; an actuator support normally holding said actuator in its inactive position and arranged to be moved by fluid forced into said body to release said actuator; said actuator having a fluid duct therein through which a portion of said fluid may pass to said cutting blade. 80

3. A pipe cutter having a hollow body; a cutting blade movably mounted in said body; a blade actuator in said body and movable into its active position by gravity; a resilient actuator support to yieldably hold said actuator in its inactive position and arranged to be moved by fluid forced into said body to release said actuator. 90

4. A pipe cutter having a hollow body; a cutting blade movably mounted in said body; a blade actuator in said body comprising a hollow rod movable by gravity into its active position; an actuator support comprising a ring movable in said body about said actuator, urged upwardly by a spring, serving to yieldably hold said actuator in its inactive position, and arranged to be moved downwardly by fluid forced into said body to release said actuator. 100

5. A pipe cutter having a body; a cutting blade; a blade holder pivotally mounted in said body to swing said blade from its inactive position in said body outwardly and downwardly into its active position; said blade having a cutting edge extending upwardly and outwardly from the longitudinal axis of said body; means to actuate said holder; and pipe engaging means to resist the rotation of said cutter in the pipe after said blade has made a predetermined cut in the pipe. 110

6. A pipe cutter having a body; a blade holder pivotally mounted in said body; a cutting blade carried by said holder above its pivot; means to swing said holder outwardly on its pivot to move said blade into its active position; and a pipe engaging dog carried by said holder above its pivot to resist the rotation of said cutter in the pipe after said blade has made a predetermined cut in the pipe. 120

7. A pipe cutter having a hollow body; an 130

actuator reciprocable in said body and movable by gravity into its active position; an actuator support in said body to yieldably hold said actuator in its inactive position 5 and arranged to be moved by fluid forced into said body to release said actuator; a blade holder pivotally mounted in said body; and a cutting blade carried by said holder above its pivot; said actuator having an inclined portion to engage said holder to swing said holder outwardly and downwardly on its pivot to move said blade into its active position.

8. A pipe cutter having a hollow body; a cutting blade movably mounted in said body; a blade actuator in said body and having a fluid passageway therethrough; and an actuator support normally holding 70 said actuator in its inactive position and arranged to be moved by fluid forced into said body to release said actuator; the fluid passageway in said actuator being open at all times and serving to convey to said blade a 75 portion of the fluid forced into said body.
